UNITED STATES PATENT OFFICE.

ANTON MARTIN SCHWEIGÅRD SCHÄNNING, OF CHRISTIANIA, NORWAY.

CAN OPENER.

Application filed February 16, 1924, Serial No. 693,265, and in Norway November 17, 1923.

The present invention consists of improvements in and relating to can openers in the form of tongs, the under jaw of which during its operation abuts against the under side of the seam of the can whilst the upper jaw is formed as or carries a knife or cutter and the invention especially consists in arrangements for securing an accurate guidance of the opener when in use so that it can be easily and safely operated by a weak and untrained hand.

According to the invention this is obtained partly by providing the under jaw of the tongs with a claw, hook or the like which 15 grips around the vertical part of the seam and thereby secures the abutment of the jaw against the under side of the seam, and partly by the arrangement that the under jaw is split into two or more parts which 20 abut against the seam respectively outside of the can at some distance from each other in the horizontal direction, whereby the opener is being guided in a position normal or nearly normal to the axis of the can while 25 being moved along the seam. The invention further consists in the arrangement that the cutter has its movement between the parts of the under jaw, whereby every tendency of the tongs to take an inclined position during 30 the cutting operation is eliminated.

In order to facilitate the cutting work it is advisable after the first perforation of the can cover having been made to limit the opening movement of the tongs so as to prevent the cutter from slipping out of the 35 cut, whereby a continual cut round the can is secured and a renewed cutting through the tin rendered unnecessary.

The arrangement for limiting the opening angle may be made in the form of an elastic rod secured to one of the levers of the tongs and provided with a catch which on the closing of the tongs snaps over a projection or the like on the other lever in the way that 40 the tongs may be freely closed whilst the catch limits its opening movement as desired.

The invention is illustrated by the way of an example in the attached drawings, where

50 Fig. 1 is a side view, and

Fig. 2 a plan-view of the opener.

In the example illustrated in the drawing the under jaw of the tongs is split in two parts 1, 1, each of which is provided 55 with an opening 2 which slips round the jaw thereof being bifurcated, each furcation

seam 3 of the can whereby the lower parts 4 abut against the under side of the seam and the claw- or hook-formed parts 5 grip over the vertical part of seam and secure the abutment of the tongs under same.

60 6 is the upper jaw of the tongs provided with a cutter 7 which in the example shown in the drawing is formed by bending down of the jaw. After each cutting operation the tongs is again opened by means of the 65 spring 8.

The limiting of the opening movement of the tongs is in the example shown effected by means of the elastic rod 9 which is provided with a catch 10 and carried through 70 the opening 12 in the other lever of the tongs. The spring action presses the rod against the edge 11 so that the catch, when the tongs is closed snaps over the edge and thus limits the opening movement. If a 75 larger opening angle of the tongs is desired the catch can be brought out of engagement with the edge 11 by a pressure on the upper part 13 of the rod.

Modifications and changes may be made 80 in the constructions within the scope of the invention, which is not limited to the form as shown in the drawing.

Having now particularly described and ascertained the nature of my said invention, 85 and in what manner the same is to be performed I declare that what I claim is:

1. In a can opener, a pair of tongs having jaws adapted to be arranged radially to a can, one jaw being bifurcated, each bifurcation terminating in a part adapted to abut the under side of the seam of a can and a hook adapted to grip around the vertical part of the seam, the second jaw having a depending cutter portion adapted to operate between said furcations.

2. In a can opener, a pair of tongs, one jaw thereof being forked and terminating in a part adapted to abut under the under side of the seam of a can, a hook thereon adapted to grip around the vertical part of the seam, the other jaw being bent downward and provided with a cutting edge adapted to operate between the ends of the forked jaw, and means to limit the opening of the jaws while the device is in position on the can to prevent displacement of the jaws in respect to the can.

3. In a can opener, a pair of tongs, one jaw thereof being bifurcated, each furcation

terminating in a part adapted to abut under the under side of the seam of a can and a hook adapted to grip around the vertical part of the seam, the other jaw being bent downward and provided with a cutting edge adapted to operate between the ends of the furcations, a spring to open the jaws and a

spring secured to one lever, a catch projection thereon to grip the other lever and adapted to limit the opening of the jaws. 10

In testimony whereof I have signed my name to this specification.

ANTON MARTIN SCHWEIGÅRD SCHÄNNING.
